UNITED STATES PATENT OFFICE.

CHARLES S. BURTON, OF OAK PARK, ILLINOIS.

CONTAINER FOR MUSIC ROLLS AND THE LIKE.

Application filed September 19, 1921. Serial No. 501,697.

To all whom it may concern:

Be it known that I, CHARLES S. BURTON, a citizen of the United States, having residence in Oak Park, in the county of Cook 5 and State of Illinois, have invented certain new and useful Improvements in Containers for Music Rolls and the like, of which the following is a specification, reference being had to the accompanying drawings, forming 10 a part thereof.

The purpose of this invention is to provide an improved construction of box, particularly adapted as a container for such articles as music rolls and the like. It consists 15 in the elements and features of construction shown and described as indicated in the claims.

In the drawings:—

Figure 1 is a longitudinal vertical section 20 of a container embodying this invention, the same being shown at closed position with the roll indicated in dotted line therein.

Figure 2 is a similar view showing the closure withdrawn and swung down to open 25 position for withdrawing the roll.

Figure 3 is a section at the line, 3—3, on Figure 1.

Figure 4 is a perspective view of a reinforce 30 with which the open end of the tubular box member is provided.

Figure 5 is a detail section at the line, 5—5, on Figure 3.

Figure 6 is an enlarged perspective view 35 of a catch device and withdrawing lugs therefor which is provided on the telescoping closure of the box.

In the construction shown in the drawings there is represented a rectangular tubular box, 1, open at the forward end and provided 40 with a telescoping closure, 2, which is open at the top and the inner end, having one end wall and three side walls, so that this closure when in closed position affords lodgment for the outer end portion of the 45 roll which is contained in the box. The open end of the box is provided with a metal reinforce, 4, preferably rectangular-tubular in form, fitting tightly within the box, its length being sufficient in view of its thickness,—being made of comparatively light 50 weight of sheet metal,—to adapt it to constitute an adequate reinforce for the open end of the box, and tending to prevent the distortion and collapse of the box which is 55 liable to occur when the closure is withdrawn and the box is empty by reason of

the lack of any end walls at this end of the box. This reinforce it is found, may be adequately secured in position in the box by a little glue applied to each of its four 60 sides before inserting it into the open end of the box. The closure, 2, has secured to its bottom, 5, a metal fitting which is preferably a strip of sheet metal 7, riveted or otherwise securely attached to said bottom 65 side of the closure, having on its inner end which is substantially even with the inner end of said bottom, a downwardly-turned lip, 7^a. The lower side of the reinforce, 4, has a co-operating upturned lip, 4^a. Both 70 these lips are quite narrow but of sufficient width so that when they are engaged which occurs upon the withdrawal of the closure to open position, they are adapted for a 75 hingewise action, permitting the enclosure 75 to swing down out of the path of withdrawal of the roll from the box. To limit the down-swinging movement of the closure at this open position, the closure sides, 2^a, 2^b, are extended beyond the bottom and cut 80 away at the upper edges obliquely at an angle which permits the closure to swing down far enough to bring the upper edge 80 of its end wall substantially onto the plane of the bottom wall of the tubular box, 85 thereby completely clearing the path for withdrawal of the roll.

It will be seen that by swinging the closure up a little from this lower position the two lips, 4^a and 5^a, can be disengaged from 90 each other by slightly springing the bottom of the closure directly upward, and thereby the closure can be completely disconnected from the box whenever desired. But in the ordinary operation of the closure, withdrawing 95 it and dropping it down for removal and insertion of the roll, no disconnection will occur, and the operator will have no occasion to discover that the closure is not permanently joined to the box. 100

For locking the closure at closed position, avoiding the danger of dropping the roll out of the box by its weight opening the closure when the box is held with the closure end downward, there is provided a catch member, 7, secured to the bottom wall of the closure, preferably at the inner side, having its forward end flexed downward so as to extend through the thickness of the bottom with a tendency to extend a little farther 110 down, and this depressed end constitutes a lip, 7^a, which is adapted to engage the lip,

4^a, of the reinforce, 4, at closed position of the closure. For disengaging the catch from the reinforce to permit the withdrawal of the closure, there is provided a lug preferably flexible and preferably in the form of a loop of cord which is inserted down through an aperture, 7^b, in the catch member, 7, and stopped by knot thereabove, thence out through an aperture, 7^c, in the lip, 7^a, and through a notch, 4^d, in the lip, 4^a, and an aperture, 2^d, formed at the lower corner of the forward end of the closure, said slot being extended a short distance vertically in said forward end to form a path in which 15 the lug may be lifted for disengaging the lip, 7^a, from the lip, 4^a.

It will be seen that the ordinary or natural pull which will be given by the user upon the lug when it is desired to withdraw the 20 closure from the box to remove the roll or insert a roll will be upward and outward, and that the upward component of the pull will disengage the catch while the outward pull will withdraw the closure. When these 25 roll containers, are assembled in a pile as in the place of sale, and the salesman desires to withdraw any given box from the pile, a direct outward pull without any upward pull upon the lug will not disengage the catch, 30 but the entire container will be withdrawn bodily from the pile; this is the intention of the construction,—that the direct outward, or outward and downward pull will draw the entire container, while an outward and 35 upward pull will withdraw the closure from the container.

It will be noticed that when the closure is withdrawn and swung down for withdrawing the roll, the end of the catch, 7^d, and the 40 inner end of the bottom of the closure tends to stand slightly projected above the plane of the upper surface of the lower wall of the tubular box member, 1, so that in withdrawing the roll from the box, the rear or inner 45 flange of the roll would be liable to catch upon this upwardly-projecting end of the catch and end of the closure bottom. To prevent this undesirable engagement of the roll flange, the bottom side of the reinforce, 50 4, has struck up from it a sloping upraise, 4^x, terminating a little back of the lip, 4^a, and the crest of said upraise being a little higher than said lip and as high as the end of the catch, 7^d, and the end of the bottom 55 of the closure will stand at the withdrawn and down-swung position of the closure. In the withdrawal movement of the roll, the flange encounters and rides up on this sloping upraise so that at the forward end 60 of the rib it is lifted high enough so that it will pass out over the end of the catch and the end of the bottom of the closure without encounter or engagement therewith.

In order that the roll may be withdrawn 65 from the tubular box to a sufficient distance

to be readily taken hold of by the operator by the withdrawal of the closure, there is provided upon the inner side of the bottom of the closure an abutment, 10, which slopes up from the inner end for easily entering under the flange of the roll in the intrust of the closure in its closing movement, the outer side of said abutment being abrupt for engaging behind the flange positively so that in the withdrawal movement of the closure 70 before it is tilted down the roll is withdrawn far enough to be grasped by the hand of the operator.

As a matter of economical construction, it will be noted that the hinge lip, 7^a, catch 80 member, 7, and roll engaging abutment, 10, are all formed of the same piece of sheet metal which is riveted to the bottom of the closure just behind the abutment, 10. It will be understood that it is not necessary to 85 make these three elements from the same piece of metal, but it is convenient and economical to do so.

I claim:—

1. A container for music rolls and the like 90 comprising a tubular box open at one end; a telescoping closure for said open end having an end wall and three side walls and open at the other end and the fourth side; a metal fitting secured inside the open end 95 of the box at one side thereof, and a metal fitting secured to the middle of the three sides of the closure at the open end thereof, said fittings having co-operating features adapted for coming into engagement upon 100 withdrawal of the closure to open position.

2. In the construction defined in claim 1, foregoing, the fitting on the box extending around all four sides of the open end, to serve as a reinforce against distortion of 105 the box at said open end thereof.

3. In the construction defined in claim 1, foregoing, a catch member on the middle of the three sides of the closure, the metal fitting on the box being adapted to engage said catch member of the closure to lock it at closed position, and means for disengaging the catch adapted to serve as means for withdrawing the closure.

4. In the construction defined in claim 1, 115 foregoing, one of the co-operating features of the box and closure being a hook device open in the direction of approach of the two features in the opening movement of the closure; whereby at open position of the 120 closure said co-operating features may be disengaged and thereupon the closure may be separated bodily from the box.

5. In the construction defined in claim 1, 125 foregoing, the fitting at the box mouth being extended longitudinally of the box a substantial distance and having an up-raise sloped for encounter of the rear or inner flange of the roll in the withdrawal movement, and terminating just behind the catch 130

feature of said fitting for elevating said roll flange to prevent its encounter with the catch in the withdrawal of the roll from the box.

6. A container for music rolls and the like comprising a tubular box having one end open, and a telescoping closure for the same open at the top and inner end for emplacement and removal of the roll without entire separation of the closure from the box, the lower side of the closure having a roll-flange-engaging projection mounted on its inner surface, said projection being sloping on the inner side toward the box cavity and abrupt on the opposite side for entering under the roll flange in closing the closure and positively engaging the roll flange in the withdrawal movement of the closure.
7. A container for music rolls and the like comprising a tubular box open at one end; a telescoping closure for said open end having an end wall and three side walls and open at the other end and the fourth side;

a metal fitting secured to one of the side walls of the box at the open end, and a catch device for engaging said fitting mounted upon the bottom wall of the closure, the engaging features of said co-operating catch member being respectively the up-turned lip on the fitting on the box and the down-turned lip on the catch device of the closure; coinciding apertures in said lips, the aperture in the lip of the box fitting being a notch, and a lug secured to the catch on the closure extending out through said aperture and adapted to pass into the notch on the engagement of the two lips for locking the closure at closed position, the end wall of the closure being slotted upwardly from the lower corner to afford a path of lifting movement of the lug.

In testimony whereof, I have hereunto set my hand at Chicago, Illinois, this 1st day of September, A. D. 1921.

CHARLES S. BURTON.
